PASTE TUBE CAP

Lawrence B. Frye, Philadelphia, Pa.

Application July 7, 1933, Serial No. 679,436

3 Claims. (Cl. 221—60)

This invention relates to caps designed for use in connection with tubes containing tooth paste, shaving cream or the like, the primary object of the invention being to provide a cap which will be held on the neck of the tube or container, at all times, thereby eliminating any possibility of the cap being lost or misplaced.

Another object of the invention is the provision of a device of this character which will provide a close fit between the cap and discharge end of the tube of the container, to insure against the contents of the tube passing from the container, when the tube is closed.

A still further object of the invention is to provide a pivoted cap having means for restricting pivotal movement of the cap, whereby the cap will be guided to its closed position and prevented from swinging too far, or past the discharge end of the tube.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view of a paste containing tube, supplied with a pivoted cap constructed in accordance with the invention.

Figure 2 is a side elevational view of the cap.

Figure 3 is an enlarged longitudinal sectional view through the cap.

Figure 4 is a plan view of the body portion or threaded section of the cap.

Referring to the drawing in detail, the reference character 5 designates a container designed for containing paste such as used in cleaning teeth, shaving cream, or the like.

This container 5 embodies a tube 6 through which the contents of the container are discharged, the tube being shown as provided with an enlarged threaded portion 7, disposed adjacent to one end of the container.

The tube 6 is cut away directly adjacent to the enlarged threaded portion 7, as at 8, defining an annular shoulder 9 spaced from one end of the enlarged threaded portion 7, as clearly shown by the drawing.

Mounted on the enlarged threaded portion 7 of the tube 6, is a collar indicated at 10, which collar has a tapered upper edge split at 11, so

that when the collar has been positioned, the portions thereof between the split portions 11 are bent inwardly to closely engage the contracted portion of the tube, caused by cutting away a portion of the tube.

Thus it will be seen that due to this construction, the collar will be restricted in its movement longitudinally of the tube, to the end that it is impossible to rotate the collar 10 in such a way as to remove it from the tube 6.

The reference character 12 designates a disk-like closure member that has its under surface cut away providing a seat for the sealing disk 13, which is constructed of suitable fibrous material, to insure a close fit between the discharge end of the tube and disk-like closure member. Arms indicated at 14 are formed on the disk-like closure member 12 and extend from opposite sides thereof, the arms being provided with eyes at their free ends, for the reception of the pins 15, that extend from the collar 10.

Thus it will be seen that the disk-like closure 12, has pivotal connection with the collar 10, through the arms 14.

Secured to the arms 14, is a curved bar 16, which bar is so constructed that it will contact with the tube 6, when the disk-like member 12 has been moved to its proper closing position over the discharge end of the tube, thereby insuring against the closure member swinging too far to permit the paste or material held within the container, to pass from the tube.

From the foregoing it will be obvious that due to the construction shown and described, the closure may be readily and easily moved to its closed position, and that by rotating the collar 10, the disk-like closure member will be drawn into close engagement with the discharge end of the tube 6.

In order to release the material from the container, it is only necessary to rotate the collar 10 in an anti-clockwise direction, and when the disk-like closure member 12 has moved away from the discharge end of the tube 6, the closure member 12 may swing laterally away from the tube.

Having thus described the invention what is claimed is:

1. A container including a discharge tube having a threaded portion near its inner end, a collar having internal threads and fitted over the threaded portion of the tube, means for restricting outward movement of the collar, arms pivotally connected with the collar and adapted to rotate therewith, a cap secured to the outer ends of the arms and adapted to move over the end

- of the discharge tube, and means for restricting swinging movement of the arms to insure the arms being held in positions parallel with the tube.
- 5 2. A container including a discharge tube, said tube having a peripheral cut out portion intermediate its ends presenting an annular shoulder, said discharge tube having a threaded portion between the cut out portion and the container, a 10 threaded collar fitted over the threaded portion of the tube, said collar having a contracted portion fitted within the cut out portion of the tube, the ends of the contracted portion adapted to en-

gage the shoulder, thereby restricting outward movement of the collar longitudinally of the discharge tube, and a closure movable with the collar and adapted to engage the end of the discharge tube, closing the discharge tube.

3. A container including a discharge tube having a threaded portion, a threaded collar operating over the threaded portion of the discharge tube, a shoulder on the tube and adapted to be engaged by the collar restricting outward movement of the collar, and a cap pivotally supported by the collar and adapted to close the tube.
